2 SHEETS—SHEET 2.

UNITED STATES PATENT OFFICE.

JOHN A. BARHORST, OF MINSTER, OHIO.

GRAIN-SPROUTER.

1,177,564.

Specification of Letters Patent. Patented Mar. 28, 1916.

Application filed August 12, 1915. Serial No. 45,188.

To all whom it may concern:

Be it known that I, JOHN A. BARHORST, a citizen of the United States, residing at Minster, in the county of Auglaize and State 5 of Ohio, have invented new and useful Improvements in Grain-Sprouters, of which the following is a specification.

This invention relates to grain sprouters, and it has for its object to produce a device 10 of this class which will be simple and inexpensive in construction and which will be composed of a plurality of superposed sections of large aggregate area for the purpose of sprouting grain supported thereon.

15 A further object of the invention is to simplify and improve the construction of the individual trays or grain supporting elements of the device.

A further object of the invention is to 20 simplify and improve the construction of the individual tray frames and to provide the wall members of said trays with grooves or kerfs to support the floor members and the deflecting members when the parts are 25 properly assembled.

With these and other ends in view which will readily appear as the nature of the invention is better understood, the same consists in the improved construction and novel 30 arrangement and combination of parts which will be hereinafter fully described and particularly pointed out in the claims.

In the accompanying drawings has been 35 illustrated a simple and preferred form of the invention, it being, however, understood that no limitation is necessarily made to the precise structural details therein exhibited, but that changes, alterations and modifications within the scope of the claims may be 40 resorted to when desired.

In the drawings, Figure 1 is a view in 45 side elevation partly in section of a grain sprouter constructed in accordance with the invention. Fig. 2 is a horizontal sectional view taken on the line 2—2 in Fig. 1. Fig. 3 is a detail view of one of the trays. Fig. 4 is a bottom plan view of one of the trays. Fig. 5 is a perspective detail view of a portion of one of the tray frames, showing also 50 a portion of the bottom member and other parts previous to being assembled.

Corresponding parts in the several figures are denoted by like characters of reference.

55 The improved sprouter comprises in its construction a bottom section or heater cas-

ing A, a water pan B supported thereon, a plurality of trays C superposed on each other and on the water tray, and a top member D disposed on the uppermost tray 60 member.

The heater casing consists of a rectangular frame of suitable dimensions, said frame having a door 15 through which access may be had to a heater, such as a suitable lamp 65 16, within the casing. The water tray supported on the heater casing A consists of a frame within which is supported a pan 17 of sufficient capacity to hold an ample supply of water.

70 Each of the trays C consists of a frame, the wall members of which, 18, are each provided with grooves or kerfs 19, 20 in the inner faces thereof and relatively near their upper and lower edges, the ends of said 75 kerfs being in registry with each other when the wall members are joined together. The joining together of the wall members at the corners of the frame may be effected in any convenient and well known manner. A bottom member 21 of sheet metal is provided, 80 said bottom member being supported in the lower kerfs of the respective wall members, and the latter when assembled are joined together, thereby providing a construction 85 whereby the bottom member will be securely supported without the use of special supporting or fastening means, and the construction being, moreover, one whereby the danger of warping will be reduced to a 90 minimum. The wall member is provided with a large number of apertures 22 and with a centrally disposed flue 23 establishing communication between the several 95 trays. Each wall member is provided with a sight opening 24 protected by a glass or transparent cover 25. The four corners of each bottom member are cut away so as to produce at each corner of the tray an opening 26 adjacent to which a guard 27 is 100 mounted, said guard being diagonally disposed and having its ends secured on the inner faces of proximate wall members. The tray is, furthermore, provided at each corner thereof with triangular deflectors 28, 105 said deflectors being mounted or supported in the grooves or kerfs 19 where they may be readily inserted after the assembling together of the frame members of the tray. For the purpose of retaining the deflectors 110 in position small nails or tacks 29 may be employed. The top member D consists of a

rectangular frame, the wall members of which are grooved or provided with kerfs 30 for the reception of a sheet metal plate 31 that constitutes a closure for the topmost 5 tray.

The wall members of the casing A, the frame B, trays C and the top member D are downwardly grooved or inclined in an inward direction at their meeting edges or 10 faces, as indicated at 32, a construction being thus provided which will enable the said members to be conveniently stacked in properly registering relation.

In the use of this device the grain that is 15 to be sprouted is spread over the surface of the bottom members of the respective trays which are then stacked on the water pan, the latter having been filled and mounted on the heater casing. The top member D 20 is, likewise, placed in position on the topmost tray, it being understood that any desired number of trays may be included in the stack. The heater is now ignited, causing vaporization of the water, the hot vapor 25 ascending through the stack of trays where it is free to rise through the central flues, as well as through the cut-off corners, the deflectors 28 serving to spread the said vapor over the contents of each tray, causing the 30 grain to sprout very quickly, the sprouting conditions being improved by the light entering each tray through the openings in the four sides thereof. Grain may thus be very 35 quickly and successfully sprouted to produce an excellent poultry food and for other purposes.

Having thus described the invention, what is claimed as new, is:—

1. In a grain sprouter, a heater casing, a 40 superposed water pan, a stack of trays superposed in the water pan, and a top member constituting a closure superposed on the topmost tray, the trays having reticulated bottom members and openings for the passage of vapors and the meeting edges of the 45 heater casing, the water pan, the trays and the top member being downwardly and inwardly inclined.

Copies of this patent may be obtained for five cents each, by addressing the "Commissioner of Patents, Washington, D. C."

2. In a sprouter, a tray comprising a frame having wall members provided with 50 kerfs in their inner faces adjacent to their upper and lower edges, a reticulated bottom member supported in the lower kerfs and having cut-away corners, and triangular deflectors supported in the top kerfs above 55 said cut-away corners.

3. In a sprouter, a tray comprising a frame having wall members provided with kerfs in their inner faces adjacent to their upper and lower edges, a reticulated bottom member supported in the lower kerfs and having cut-away corners, and triangular deflectors supported in the top kerfs above 60 said cut-away corners, in combination with diagonally disposed guard members adjacent to the cut-away corners and having their ends secured on proximate wall members.

4. In a sprouter, a tray having a reticulated bottom member with cut-away corners, 70 triangular deflectors supported at the corners of said tray above the bottom members, and a centrally disposed flue.

5. In a sprouter, a tray having reticulated bottom member with cut-away corners, 75 triangular deflectors supported at the corners of said tray above the bottom members, and a centrally disposed flue, said tray being provided with light openings in the wall members thereof and with transparent covers 80 for said light openings.

6. In a device of the class described, a tray having a reticulated bottom member with cut-off corners, triangular deflectors at the corners of said tray supported above 85 the bottom member, a centrally disposed flue rising from the reticulated bottom member, and light openings in the wall members of said tray, said light openings having transparent covers. 90

In testimony whereof I affix my signature in presence of two witnesses.

JOHN A. BARHORST.
